CLAIM

The ornamental design for a modular home gym platform, as shown and described.

DESCRIPTION

FIG. 1 is a front, side perspective view of modular home gym platform.

FIG. 2 is a front elevation view thereof.

FIG. 3 is a rear elevation view thereof.

FIG. 4 is a side elevation view thereof.

FIG. 5 is a side elevation view thereof from a side opposite to FIG. 4.

FIG. 6 is a top plan view thereof; and,

FIG. 7 is a bottom plan view thereof.

All portions of the drawings shown in broken lines are for illustrative purposes only and form no part of the claimed design.

1 Claim, 5 Drawing Sheets(56)
